UNITED STATES PATENT OFFICE.

ALFONS RUF, OF ZURICH, SWITZERLAND.

MANIFOLDING DEVICE.

Application filed January 29, 1926, Serial No. 84,697, and in Switzerland January 31, 1925.

The present invention relates to a manifolding device for loose-leaf journals for billing goods and for other purposes where a carbon copy of the writing is to be made 5 and more particularly to devices of said class having a board with two clips of which one clip holds the copy sheet for instance a journal leaf as well as the carbon paper while the second clip holds the sheet on 10 which the original entry or bill is to be made.

In the modern system of loose-leaf book keeping a plurality of entries are copied on one and the same copy sheet in regular sequence on consecutive lines while the original entries are written each on separate sheets. It has been the practice to make the copy sheet and the original sheets of different size and boxes of different size are 20 necessary to store the sheets.

The main object of the invention is to provide a device which allows sheets of the same size to be used for the original entry and for the copy sheet, means being provided to ascertain the exact position of the sheets with reference to each other to get the copy of the original writing at the proper place on the copy sheet.

The novel features of the invention are 30 more fully described in the following specification and claims and illustrated in the accompanying drawings in which:

Fig. 1 is a transverse section through the device shown in plan in Fig. 2.

Fig. 2 is a top view.

Fig. 3 is a sectional elevation of a detail drawn on a larger scale.

Fig. 4 is a transverse section of the clip bar.

Fig. 5 is a broken transverse section and Fig. 6 is a side elevation of the modified form of hand support.

Figs. 7 to 9 illustrate a modified construction of the clip. Fig. 7 is a top view of the bar, Fig. 8 is a side view and Fig. 9 a cross section thereof.

Fig. 10 is a cross-section to a modified construction of the line pointer of which

Fig. 11 is a side view.

The device shown in Figs. 1 to 4 comprises a plate 1 of aluminium having near one of its corners a block 2 to which a bar 3 is hingedly connected. To the lower side of bar 3 two clips 4 are fixed projecting about one tenth of an inch over the face 35 of the bar 3. The bar 3 is held in its clamping

position by a pin 6 slidably mounted in a block 5 fixed to plate 1. A screw bolt 7 engaging a groove of pin 6 prevents the loss of pin 6. The bar 3 is provided with two notches in which two square studs 21 are fixed on plate 1 project. One face of each stud 21 is flush with the plane 35 of bar 3 and these faces serve as an abutment for the copy sheets 14 for instance the leaves of the loose-leaf journal. The clips hold the said leaves 14 together with the carbon paper while the face 35 serves as an abutment for the upper sheets 33 on which the entry is to be written. On the bar 3 two lugs 8 are 70 fixed in which a lever 10 is pivoted by means of a pin 9. The lever 10 is provided with a bar 10' which runs parallel to bar 3 and which is pressed down on plate 1 by means of a torsion spring 11 acting on the lever 10. 75

The bar 10' is intended to hold the upper sheet 33 which is removed after the entry has been made the lever 10 being pressed down, by hand. On the bar 10' a division is shown corresponding to the lines on the leaves 14 and 33. On the plate 1 a ledge 12 is fixed running parallel to the bar 3 along the opposite edge of the plate 1. On the face of said ledge 12 notches 13 are provided which

are in line with the division marks on the bar 10', and with lines 1 to 21 marked in the plate 1. On the ledge 12 a carrier 15 is slidably mounted and to the carriage 15 a hand support 19 is hingedly connected. The support 19 projects over the plate and 85 ends near bar 3. The carriage is provided with a knob 16 having a central bore in which a ball 17 is housed. The ball 17 is held in engagement with the notches 13 of the bar 12 by means of a spring 18 arranged within the bore of the knob 16. The ball 17 retains the support 19 in its 90 position. The support 19 not only supports the hand when writing but is intended to show the line on the upper sheet 33 to be written upon in order to get the copy on the proper line on the lower sheet 14 which is covered by the carbon paper. A lug 20 bent off from the support 19 facilitates the tilting of the support 19 into the 95 position shown in broken lines Fig. 3 if the leaf 14 is to be removed.

The device is used as follows:— The leaf 14 is put in place on the plate in such a manner that one edge thereof abuts 110 on the studs 21 while its lines are in line with the marks on the plate 1 and with the

division marks on bar 10' and with the notches 13. The carbon paper is placed on leaf 14 and the bar 3 is then fastened by pin 6; leaf 14 with the carbon paper is held fast. The carriage 19 is placed into such a position that the upper edge of the support 19 uncovers the upper-most line of leaf 14. Now the upper sheet 33 is placed below the bar 10' in such a manner that its left hand edge abuts on face 35 of bar 3 and that the line on which an entry is to be written is above that line of leaf 14 on which the copy has to appear. The clip 9, 10, 10' retains the upper sheet 33. If the entry is made the bar 10' is raised, sheet 33 is removed, the support 19 is moved down for one line by pushing on knob 16. The device is now ready to receive another sheet 33. It will be seen that the left hand edges of the sheets 14 and 33 are one above the other and the columns printed on the said sheets may be exactly alike.

The carriage with the hand supports may be made as shown in Figs. 5 and 6. The bar 22 of T-shaped cross-section is rigidly fixed to the plate 1. A sleeve 24 is slidably mounted on the bar 22 and in slots of said sleeve 24 the ends of a curved blade spring 25 are held. The spring 25 presses a ball 23 into notches 13 of the bar 22. The sleeve 24 is provided with two lugs 29 in which a pin 28 having knobs 26 at its ends is rotatably mounted. On the pin 28 a sleeve 27 forming part of the support 19 is fixed. By turning a knob 26 the support 19 is lifted from the leaf 14.

As shown in Figs. 7 and 8, and 9, the bar 3 may be made of sheet metal. A strip of sheet metal is bent into a bar 30 with U-shaped cross-section. Small tongues 31 to hold the leaves 14 are worked out of the side wall of bar 30 and the lugs 32 in which the lever 10 is to be journalled are formed by tongues cut in the bar 30 and bent to run parallel at right angles to bar 30.

In place of the line pointer 19 the device shown in Figs. 10 and 11 may be used. The bar 10' is provided with a slot 37 and in said slot a small rider 36 of celluloid, aluminium etc. is slidably mounted. The pointer 36 is bent to form a spring and is held by friction in its position in the slot. The end portion of the pointer is bent to run above the sheet 33. The pointer 36 may be displaced by the nib of the writer and is preferably shaped in such a manner that it covers the place where the date is to be written on sheet 33. The writer has to displace the pointer 36 each time he has to

make an entry and the displacement of the pointer is not likely to be forgotten.

I wish it understood that various changes may be made in the construction of the parts, for instance the clip to hold the papers may be made of a single blade spring holding the copy sheet and the carbon paper along the top edge while the original entry sheet is held by hand and so on.

What I wish to secure by U. S. Letters Patent is:—

1. A manifolding device comprising a plate, a bar hinged at one edge of the plate, abutments fixed to said plate, one face of said abutments being flush with a side wall of said bar, means carried by the bar to clamp a leaf and a sheet of carbon paper on the plate, said means protruding sidewardly of the said bar, and a member pivotally mounted on the bar and carrying a portion to overlie and bear upon an original sheet to be placed on the carbon paper.

2. A manifolding device comprising a plate, a bar hinged at one edge of the plate, abutments fixed to said plate, one face of said abutments being flush with a side wall of said bar, means carried by the bar to clamp a leaf and a sheet of carbon paper on the plate, said means protruding sidewardly of the said bar, and a member pivotally mounted on the bar and carrying a portion to overlie and bear upon an original sheet to be placed on the carbon paper, said extended portion having markings registered with lines on the plate, whereby to indicate a desired line of marking on the original sheet in registry with a particular line of writing on the copy sheet or leaf.

3. A manifold device comprising a plate marked with transverse lines to indicate lines of writing, means carried by one edge of the plate to overlie and bear upon a copy and superimposed carbon sheet, a manifold operable member mounted in adjustment to said bearing means and having an extended portion to overlie and hold an original sheet upon the carbon sheet, such extended portion having markings registering with the lines on the plate, whereby to indicate a desired line of marking on the original sheet in registry with a particular line of writing on the copy sheet, and a pointer carried by said extended portion and movable to indicate the successive lines of writing on the original sheet in registry with the similar lines on the copy sheet.

In witness whereof I affix my signature.

ALFONS RUF.
